PARKING SPROCKET FOR TRAVEL TRAILERS

William H. Kessler, Grosse Pointe Park, Mich., assignor to Meathe, Kessler and Associates, Inc., Grosse Pointe,
Mich., a corporation of Michigan

Filed Feb. 6, 1967, Ser. No. 5,697
Term of patent 14 years

(Cl. D13—1)

The single figure is a perspective view of a parking sprocket for travel trailers showing my new design, the roadway being broken away to indicate indeterminate length.

The dotted line showings are for illustrative purposes only.

I claim:

The ornamental design for a parking sprocket for travel trailers, substantially as shown and described.
